REVERSIBLE FLOW PUMP

Royden O. Couch, Grant, Fla.

Application May 14, 1940, Serial No. 335,029

5 Claims. (Cl. 103—3)

My invention relates to pumps, the primary use of which is to control the relative levels of two separate bodies of water or, in general, to maintain a higher water level on one side of the pump and associated barrier or dam than on the other side. My invention is particularly applicable to low-head, high-volume pumps such as are used in irrigation or drainage channels or ditches, canals, flumes, sluice-ways, etc.

The main object of my invention is to provide a reversible flow pump which is simple to construct, assemble, and operate and which is inexpensive and easily installed. Another object is to enable the reversal of direction of flow of water or any other fluid driven by the pump without reversing the direction of rotation of the pump elements and without removing any part of the pump assembly from the location where it is installed. A further object of my invention is to provide means whereby back-flow of the fluid through the pump and past the barrier or dam will be prevented even if, accidentally or otherwise, the pump ceases to operate. Still another object is to provide means whereby gravity-flow between the two sides of the barrier or dam may be secured without removal of any part of the pump assembly.

Among the advantages of my invention are that my reversible flow pump is adapted for use with a portable dam which can easily be placed in the channel, etc., at the desired location. Utilizing my improved pump, the flow of the water or other fluid may be reversed without removing either the dam or any part of the pump assembly from the channel and the reversed flow may be accomplished with minimum difficulty and in the minimum time. Another advantage is that, if the pump ceases to operate, back-flow through the pump is automatically prevented; also, the pump assembly may be so set that direct gravity-flow from one side of the dam to the other is accomplished.

Various other features and advantages of my invention will appear from the following description of the preferred form of my improved reversible flow pump.

In the drawings—

Figure 1 is a side elevation of my improved reversible pump together with the panel constituting the portable dam;

Fig. 2 is a cross section thereof taken on the line 2—2 of Fig. 1, the cylindrical shell being rotated through an angle of 90° from the position shown in Fig. 1 and the float valve being shown

in full lines in open or partially open position and in dotted lines in closed position;

Fig. 3 is a transverse section taken on the line 3—3 of Fig. 2, looking in the direction of the arrows, the float valve not being shown in this figure; and

Fig. 4 is a top view.

Referring to the drawings, the removable and portable panel, in the particular form shown, consists of two plates 10 in the same plane, which plates, with the associated elements, may be placed in a channel, etc., so as to separate it into two parts. In effect, they constitute a panel having an aperture therein within which my reversible flow pump is mounted. Normally, the plates 10 carry a strip 11 which is affixed to the bottom edges of the plates 10 and constitutes the bottom of the aperture above mentioned. The aperture is closed at the top by a plate 12 welded or otherwise affixed to the tops of the plates 10. The plate 12 has a central circular opening to receive the circular shell of the pump which will now be described.

In its preferred form of my reversible flow pump comprises a cylindrical shell 14 which is closed at the bottom by a plate 15. This shell is provided with an intake port 27 located on one side thereof adjacent the bottom, and a discharge port 28 located on the opposite side thereof and at a higher level than that of the intake port. As indicated in the drawings, each of these ports extends through an arc of roughly 135°. At the top of the shell I provide an annular plate 16, the central opening of which is large enough to permit the insertion into the shell and removal therefrom of the pumping unit which will be hereinafter described. The opening in the plate 16 is closed by a circular plate 16' which is preferably bolted, around its periphery, to the annular plate 16.

The bottom plate 15 has an opening at the center from which a tube 17 projects upwardly into the shell. This forms a socket 17' which is adapted to receive a stud 18 supported by an angle iron 11' which is welded or otherwise affixed to the cross strip 11 of the panel. The stud 18, in cooperation with the socket 17', holds the bottom part of the shell 14 in position with respect to the panel and also acts as a pivot upon which the shell may be rotated. At the top, the shell 14 is held in position by a ring 13 which depends from the top plate 12 of the panel.

It will be understood from the foregoing description that the cylindrical shell 14 may be rotated within the panel so that the parts of

the channel with which the intake and discharge ports communicate may be reversed. To facilitate rotation of the shell, I provide, on the top plate 16' of the shell, sockets 37 into which a turning bar (not shown) may be inserted to rotate the shell. In order to lock the shell in desired position I provide two lugs 38 welded or otherwise affixed to diametrically opposite points on the periphery of the annular plate 16. The top plate 12 of the panel is provided with four threaded holes 40 at points 90° apart and adjacent the inner edge of the plate 12. These holes are adapted to receive threaded bolts 39 which pass through the lugs 38. It is thereby possible to lock the cylindrical shell in any one of four desired positions.

Within the shell 14 and intermediate between the top of the intake port and the bottom of the discharge port is a mid-deck in the form of an annular plate 41, braced by a number of ribs 42. This mid-deck accomplishes the dual purpose of supporting the pumping unit and of separating the interior of the shell into an intake chamber and a discharge chamber. At the bottom of the shell, there is preferably provided a hydrocone, as shown at 43.

The pumping unit comprises a shaft-housing 44 which extends from the pump elements substantially to the top of the shell 14. At the top of the housing is provided a bearing housing 21, preferably containing a ball thrust bearing (not shown). Surrounding the upper part of the bearing housing, and affixed to the removable plate 16' at the top of the shell is a clamping collar 45. A shaft 19 extends throughout the housing 44, projecting upwardly therefrom so that a pulley 22 or other suitable means for rotating the shaft may be affixed thereto. The shaft is carried within the housing in suitable bearings 46. The shaft 19 projects downwardly below the lower end of the shaft-housing 44 and there is there mounted on the shaft a rotary impeller or pump, preferably of the axial flow, turbine type (generally similar, for example, to that shown in my prior Patent No. 1,893,614, issued January 10, 1933), having blades 23, preferably so formed that, when they are rotated, they will drive the water or other fluid upwardly. A lock nut 47 is preferably provided to hold the impeller unit on the shaft. Below the lock nut, a suitable bearing 48 is ordinarily used.

A pump casing 25, in the form of a Venturi section, is rigidly affixed to the shaft-housing. As is understood, the kinetic energy which is present in the moving water or fluid in the form of velocity can be efficiently converted into static head by correctly designing, as to length and divergence, the Venturi section. The rotary pump is preferably located within the central, cylindrical portion of the casing 25. The lower, flared portion of the casing extends down into the intake chamber of the shell 14 to approximately the level of the top of the hydrocone 43. The upper, flared portion of the casing 25 extends into the discharge chamber of the shell 14 and the top of the casing is substantially at the level of the lower edge of the discharge port 28. Within the casing 25 are preferably provided, both on the intake side and on the discharge side of the rotary pump, radial guide vanes 26. Surrounding and affixed to the casing 25, preferably somewhat above the level of the rotary pump, is an annular flange 29, stiffened with suitable ribs 30. This flange is designed to rest on the mid-deck 41, thereby supporting the pumping unit

within the shell 14 and also preventing flow of fluid within the shell 14 between the intake and discharge ports therein except through the pump.

Movably mounted on the shaft-housing 44 is a valve 31. This valve comprises a sleeve 32 surrounding the shaft-housing. The sleeve carries a horizontal annular flange 33 which is of substantially the same diameter as the opening at the top of the pump casing 25. Underneath the flange 33, a downwardly extending, substantially conical web 34 is preferably provided. This web, together with the lower portion of the sleeve 32 and flange 33, provides an air space 35 in the valve 31 so that its specific gravity is only slightly more than that of the fluid to be driven by the pump; the web 34 also acts to deflect the fluid as it is driven upward by the rotary impeller from the pump casing 25. When the pump is operating, the pressure of the fluid driven by the pump causes the valve 31 to rise and permit the fluid to be expelled through the discharge port 28. In Fig. 2 the valve is shown in full lines in raised,—i. e., open or partially open,—position. It is shown in the same figure in closed position in broken lines.

To seal the joints between the rotatable cylindrical shell 14 and the panel, I provide angle irons 49 attached to the inner edges of the panel plates 10. Affixed to the angle irons are strips 50 of suitable packing material which bear against the outer surface of the shell 14 and thus prevent flow of fluid from one side of the panel to the other, outside of the shell.

In order to install my improved reversible flow pump in a channel, drainage ditch, etc., it is only necessary to provide, at the sides of the channel, etc., a suitable mounting for the panel of my pump. My entire unit may then be lowered into place, the rings or eyelets 51 being provided for that purpose. It will, of course, be understood that, if preferred, the panel constituting the dam may first be lowered into place, after which the shell 14 may similarly be lowered, the top plate 16' thereof being detached therefrom; thereafter the pumping unit may be lowered into the shell, the plate 16' put in place, and the entire reversible pump thus assembled at the place where the pumping is to be done. The shell is then rotated to the desired position so that, when the pump is put into operation, the water or other fluid will be driven in the desired direction from one side of the panel or dam to the other. Suitable means (not shown), such as a gasoline engine, electric motor, etc., will of course be provided to rotate the vanes of the impeller. Such means may be connected to the pump shaft in any desired manner, as by a belt engaging the pulley 22.

When it is desired to reverse the direction of flow of the fluid, it is only necessary to remove the bolts 39 from the locking lugs 38; to insert a turning bar in one of the sockets 37, to turn the casing 14 throughout 180°, and to replace the locking bolts 39. It will be seen that the direction of flow of the fluid may thus be reversed without altering the direction of rotation of the pump, without removing or re-setting the pump, without removing the casing 14 from the panel and, in fact, without even stopping the operation of the pump.

If gravity flow from one side of the dam to the other is desired this can be accomplished merely by stopping the pump, provided the level of the water on the higher side is above the level of the top of the pump casing 25, and the intake port

27 is so positioned as to open into the channel on that side of the panel. Gravity flow may also be secured, even if the water level on the higher side is below the top of the casing 25, by removing the locking bolts 39, rotating the shell through an angle of 90°, and locking it in that position, this being the position shown in Fig. 1. As will readily be seen, when the casing is in this position, water may flow past the dam directly through the intake port 27 in the shell and also, if the water level is high enough, through the discharge port 28.

If, for any reason, operation of the pump should accidentally cease, back-flow will automatically be prevented by the valve 31.

It will be evident to those skilled in the art that many modifications may be made in the construction and arrangement of the various parts of my reversible flow pump. I therefore do not wish to be limited to the preferred arrangement or details shown and described herein, but wish to secure protection for all such variations therein or modifications thereof as may come within the scope of the appended claims.

I claim:

1. A combined dam and reversible pump comprising in combination a separated pair of substantially rectangular plates lying in the same vertical plane, a cross-piece connecting the bottoms of said plates, and an horizontal plate connecting the tops of said first-mentioned plates, said horizontal plate having a circular opening, said vertical plates, cross-piece, and horizontal plate together constituting a dam provided with a rectangular opening; a cylindrical shell located in and substantially co-extensive with said rectangular opening, said shell being closed at the bottom and having an opening in the top, and being provided with peripherally spaced intake and discharge openings in said shell, said shell being pivoted on said cross-piece whereby it is rotatable within said rectangular opening to interchange the positions of said intake and discharge openings with respect to said dam; a removable cover plate for the opening in the top of said shell, said cover plate being provided with a central aperture; and a pumping element, mounted in and removable from said shell, for impelling fluid from said intake opening to said discharge opening, said element having outside dimensions less than those of the said cover plate and being provided with a shaft extending through the aperture in said cover plate.

2. A combined dam and reversible pump comprising in combination a separated pair of substantially rectangular plates lying in the same vertical plane, a cross-piece connecting the bottoms of said plates, and an horizontal plate connecting the tops of said first-mentioned plates, said horizontal plate having a circular opening, said vertical plates, cross-piece, and horizontal plate together constituting a dam provided with a rectangular opening; a cylindrical shell located in and substantially co-extensive with said rectangular opening, said shell being closed at the bottom and having an opening in the top, and being provided with peripherally spaced intake and discharge openings, said shell being pivoted on said cross-piece whereby it is rotatable within said rectangular opening to interchange the positions of said intake and discharge openings with respect to said dam; flexible sealing strips carried by the inner edges of each of said vertical plates and bearing against the outer surface of said shell; a removable cover plate for

the opening in the top of said shell, said cover plate being provided with a central aperture; and a pumping element, mounted in said shell, for impelling fluid from said intake opening to said discharge opening, said element having outside dimensions less than the inside dimensions of the opening in the top of said shell whereby the pumping element may be removed from said shell without removal of the latter from the dam; said pumping element being provided with a shaft normally extending through the aperture in said cover plate.

3. A combined dam and reversible pump comprising in combination a separated pair of substantially rectangular plates lying in the same vertical plane, a cross-piece connecting the bottoms of said plates, and an horizontal plate connecting the tops of said first-mentioned plates, said horizontal plate having a circular opening, said vertical plates, cross-piece, and horizontal plate together constituting a dam provided with a rectangular opening; a cylindrical shell located in and substantially co-extensive with said rectangular opening, said shell being closed at the bottom and having an opening in the top, and being provided with peripherally spaced intake and discharge openings in said shell, said shell being pivoted on said cross-piece whereby it is rotatable within said rectangular opening to interchange the positions of said intake and discharge openings with respect to said dam; a removable cover plate for the opening in the top of said shell, said cover plate being provided with a central aperture; a pumping element for impelling fluid from said intake opening to said discharge opening, said element having outside dimensions less than the inside dimensions of the opening in the top of said shell whereby the pumping element may be removed from said shell without removing the latter from the dam, said pumping element being provided with a shaft normally extending through the aperture in said cover plate; and horizontal means within said shell supporting said pumping element and dividing the interior of the shell into intake and discharge chambers.

4. A reversible flow pump for a channel comprising in combination a panel constituting a dam and having an aperture therein, the said aperture having vertical edges and extending above the level of the fluid in the channel; a substantially cylindrical shell carried by said panel, closing said aperture, and rotatable without removal from said aperture about a vertical axis; intake and discharge ports in said shell located on diametrically opposite sides thereof, said ports having substantial peripheral extension and being normally positioned on opposite sides of said panel; means within said shell for impelling fluid from said intake port to said discharge port; means by which said shell may be rotated about its axis; and means for locking said shell in at least three positions, in one of which the intake port is centrally located in the channel on one side of the dam and the discharge port is centrally located in the channel on the opposite side of the dam, in another of which the respective positions of the intake and discharge ports are reversed, and in another of which one of the ports is adjacent the panel and opens into the channel on both sides of the panel, whereby fluid may be forced to flow from either side of said panel to the other or may be free to flow, by gravity, past said panel.

5. A combined dam and reversible pump com-

prising in combination a separated pair of plates in the same vertical plane, the inner edge of each plate being vertical, said plates constituting the sides of a dam; a substantially cylindrical shell having a vertical axis and being rotatably supported by said plates in the space between them, the diameter of the shell being substantially equal to the distance between said inner edges of the plates, said shell being closed at the bottom and having an opening in the top and being provided with peripherally spaced intake and discharge openings, said shell being rotatable about its axis within the space between said plates to interchange the positions of the intake

and discharge openings with respect thereto; a member associated with the top of the shell and provided with an aperture; and a pumping element comprising a casing having openings adjacent the intake and discharge openings in the shell and a rotary impeller within said casing, said element having outside dimensions less than the inside dimensions of the opening in the top of the shell whereby the pumping element may be removed from the shell without removing the latter from the dam, said impeller being provided with a shaft normally extending through said aperture.

ROYDEN O. COUCH.
